FOUNTAIN PEN

Hans A. Bauer, Prairie View, Ill., assignor to
Autopoint Company, Chicago, Ill., a corpora-
tion of Illinois

Application January 22, 1947, Serial No. 723,515

3 Claims. (Cl. 120—42.16)

1

The present invention relates to a fountain pen and especially to a novel fountain pen of a unique and simplified construction and comprising a minimum number of parts.

Among the objects of the present invention is the provision of a simplified construction of fountain pen requiring no filling mechanism and thereby eliminating the use of a rubber sack, lever, button or other style of filler device with which fountain pens are now provided.

The invention further comprehends a novel means and mechanism for feeding ink to the pen nib in such manner as to assure a smooth and uniform flow thereto, and to provide an ink reservoir in the barrel affording maximum ink capacity whereby a single filling of the barrel will last for a much longer period of time than with other types of fountain pens employing ink in liquid form.

Another feature of the present invention is the provision of a novel feed mechanism for controlling the flow of ink to the pen nib and in which there is avoided or substantially eliminated any tendency of the ink to leak.

A further object of the present invention is the provision of a fountain pen having a novel feed assembly adapted to retain a relatively small amount of ink or writing fluid providing a primary ink supply, and the hollow encompassing barrel providing a secondary ink supply or reservoir for automatically replenishing the primary ink supply whenever the pen is laid on a desk or replaced in the pocket. In this novel construction and arrangement the primary ink supply alone exerts or applies pressure, while the larger body of ink in the barrel functions merely as an auxiliary supply readily available for replenishing the primary supply in the feed assembly.

In the novel disclosed embodiment, the feed mechanism comprises a unitary assembly including a pin nib and feed bar rigidly mounted and retained in operative position in an elongated tube securely held in a tapered front end or cap threaded into the open end of a hollow barrel, the tube projecting upwardly into the barrel to adjacent the closed end thereof. The upper end of the feed bar is spaced from the end of the tube a distance sufficient to provide a primary ink reservoir having a relatively small capacity but adapted to be replenished from the relatively large secondary ink supply maintained in the space provided in the hollow barrel encompassing the tube. By making the barrel hollow and of thin-walled construction, maximum ink capacity is provided.

2

Another object of the present invention is the provision of a novel fountain pen having a primary and a secondary or auxiliary ink supply, the latter for quickly replenishing the primary supply when required. In view of the novel assembly and arrangement of the parts providing the primary and auxiliary supplies, no valve or other mechanism is required for making available the auxiliary supply or for replenishing the primary supply.

The invention further comprehends a fountain pen assembly having a minimum number of parts so constructed and arranged as to materially reduce the cost of producing the fountain pen, radically reduce the possibility or necessity for repair and greatly prolong the life of the assembly.

In the present construction of fountain pen, all forms of filler devices are completely eliminated. This includes but is not limited to the filler sack, lever or button types of fillers now employed.

Further objects are to provide a construction of maximum simplicity, efficiency and ease of assembly and operation, and such further objects, advantages and capabilities as will later more fully appear and are inherently possessed thereby.

The invention further resides in the construction, combination and arrangement of parts illustrated in the accompanying drawing, and while there is shown therein a preferred embodiment, it is to be understood that the same is susceptible of modification and change, and comprehends other details, arrangements of parts, features and constructions without departing from the spirit of the invention.

In the drawing:

Figure 1 is an enlarged vertical sectional view taken longitudinally through the novel fountain pen.

Figs. 2, 3 and 4 are horizontal sectional views taken in planes represented by the lines 2—2, 3—3 and 4—4 of Fig. 1.

The novel illustrative embodiment of fountain pen 1 shown in the drawing comprehends a unit assembly 2 comprising a tapered end cap 3, pen nib 4, feed bar 5 and an elongated feed tube 6 mounted within the tapered front end or cap 3, the pen nib and feed bar being securely held therein by means of the elongated tube 6. This tube 6 may be of stainless steel or other non-corrosive material unaffected by the ink or writing fluid.

As shown in Fig. 1, the feed bar 5 formed of any suitable material and provided with a flat

surface forming a slot 7, extends a substantial distance into the tube 6 but with its upper or inner end 8 spaced from the upper or inner end 9 of the tube to thereby provide a primary ink reservoir 10 adapted to contain a quantity of the ink or writing fluid sufficient for a predetermined period of continuous writing. For example, I find that by making this primary ink reservoir of such capacity as to retain approximately five drops of ink, sufficient writing fluid is made available for approximately two hours of continuous writing. Should that amount of ink become exhausted or only partially used, and the pen is tilted, laid upon a desk or other support, or placed in the pocket of the user, this primary ink supply is automatically replenished or refilled to its maximum capacity from the secondary ink reservoir or supply 11 carried in the hollow barrel 12.

The tapered end cap 3 is provided with a longitudinal bore 13 adapted to receive the lower end portion 14 of the tube 6 enlarged and press-fitted or otherwise secured within the bore. The outer end of the tube is tapered or inclined at 15 and thereat abuts against a complementary shoulder or stop 16 formed adjacent the outer or lower end of the cap 3. Within this enlarged part 14 of the tube is press-fitted the enlarged lower end 17 of the feed bar 5 having a slot 18 aligned with the longitudinally extending slot 7 and with the shank or body of the pen nib 4 for uniformly feeding ink thereto. As shown in Fig. 1, the shank or body of the pen nib 4 is forced into and retained in the tube 6 and between it and the feed bar 5. By mounting the nib in such manner, only the writing point thereof is exposed.

The tapered cap 3 with the pen nib 4, feed bar 5 and tube 6 rigidly or permanently mounted therein and assembled therewith as a complete unit to form the end assembly 2, is provided with a reduced threaded male end 19 adapted to be assembled in the threaded female end 20 of the barrel, the other end 21 of the barrel being closed. Thus the assembled end unit 2 may be quickly assembled onto the barrel or disassembled when it is desired to fill the barrel with ink or writing fluid. This filling is accomplished by holding the disassembled barrel in a substantially vertical position with the threaded open end 20 thereof uppermost, and then supplying it with the desired quantity of ink. Although such filling may be accomplished in any suitable manner, it is intended that a cartridge or receptacle containing a measured quantity of ink be employed. This cartridge may be threaded to or otherwise secured to the open end of the barrel and then by inverting the cartridge and barrel the liquid ink or writing fluid flows into the barrel, after which the cartridge is discarded and with the barrel retained in inverted position with the open end uppermost, the assembled unit 2 is screwed into the barrel. In this position, the amount of ink supplied to the barrel will be such as to provide a space below the open end of the barrel so as to provide an air space in the barrel sufficient to permit proper operation when the cap assembly is applied thereto. Thus when the assembled pen is placed in a vertical or upright position with the cap assembly 2 depending as shown in Fig. 1, an air space 22 will be provided in the barrel, and a limited quantity of ink will be trapped within the primary reservoir 10 in the upper end of the tube 6.

With the fountain pen in writing position, it

will be apparent that the greater quantity of ink is outside the tube 6 and with only a relatively small quantity of the ink in this tube. Only this small quantity of ink actually in the tube at 10 applies pressure through the slots 7 and 18 and feed bar 5 upon the pen nib 4, while the remainder or secondary ink supply 11 retained within the barrel 12 and surrounding the tube 6 is ineffective.

By limiting the quantity of ink held within the open end of the tube 6 to an amount approximating a maximum of five drops, sufficient ink is made available for substantially two hours of continuous writing. However, when that supply becomes exhausted or diminished, it may be readily replenished by tilting the pen, or if the fountain pen is laid upon a desk or put back into the pocket, the primary ink supply 10 in the tube 6 will be automatically refilled to its maximum capacity.

It is, of course, understood that the usual cap may be provided for enclosing or covering the nib end when not in use. However, without such cap the present device may be employed as a desk pen with the nib end adapted to be received in any suitable receptacle.

The barrel 12 and cap 3 may be formed of any plastic composition or other material suitable for the purpose. When formed of a plastic composition, the threaded female end 20 of the barrel is preferably formed as a separate internally threaded collar that is suitably cemented or otherwise affixed to the lower open end of the barrel.

From the above description and the disclosure in the drawing, it will be apparent that the present invention comprehends a novel and simplified construction of a fountain pen assembly.

Having thus disclosed the invention, I claim:

1. A fountain pen comprising a hollow barrel open at one end and providing an ink reservoir and a removable end assembly for the barrel, said end assembly including a pen nib, a feed bar and a feed tube joined together with the feed bar and pen nib received and anchored within the tube and the feed bar of a cross section closely conforming to the interior of the tube, said feed bar and encompassing feed tube projecting into the open end of the barrel and spaced from the interior of the barrel whereby the ink supplied to the barrel collects in the space between the tube and the barrel, the inner end of the feed bar being spaced from the adjacent open end of the tube within the barrel to provide between said ends an ink receptacle of limited capacity open at all times to the interior of the barrel for receiving and retaining a limited quantity of ink supplied to the open end of the tube from the ink in the barrel and replenished therefrom upon mere tilting of the pen from its normal writing position.

2. A fountain pen of two-part construction, one part comprising a hollow barrel open at one end for filling with a writing fluid and the other part providing a removable writing end assembly for the pen, the latter including an elongated tube, a pen nib and a feed bar mounted within the tube and having a cross section closely conforming to the interior of the tube, the feed bar and tube being spaced from the interior of the barrel with the upper end of the feed bar stopping short of the upper end of the tube to provide a space therebetween and both projecting a substantial distance into the barrel with the upper open end of the tube open at all times to

the interior of the barrel, the space in the barrel surrounding the tube providing a secondary ink reservoir and the space provided in the upper open end of the tube above the upper end of the feed bar providing a primary ink reservoir for containing a limited quantity of ink and adapted to be replenished from the main ink supply upon mere tilting of the pen from its normal writing position.

3. A fountain pen comprising a hollow barrel having one end closed and the other end open and providing a receptacle for receiving a substantial quantity of ink, and a removable nib end assembly including a pen nib, feed bar and hollow tube closely encompassing the feed bar and securely mounted in the open end of and spaced from the interior of the barrel to provide an ink receptacle therebetween, the inner, open end of the hollow tube projecting into the barrel to adjacent to but spaced from the upper closed end thereof and the feed bar extending into the tube

through a substantial portion of the length thereof but short of the inner end of the tube to provide an ink reservoir in the tube between the inner end of the feed bar and the inner open end of the tube and maintained in open communication with the barrel, said reservoir receiving a limited quantity of ink from the barrel and upon such limited quantity being used, this reservoir is replenished from the barrel by a mere tilting of the pen.
